UNITED STATES PATENT OFFICE.

JACOB B. ENGSTROM, OF MANCHESTER, IOWA.

FENCE-POST MOLD.

SPECIFICATION forming part of Letters Patent No. 784,667, dated March 14, 1905.

Application filed October 28, 1904. Serial No. 230,419.

To all whom it may concern:

Be it known that I, JACOB B. ENGSTROM, a citizen of the United States, residing at Manchester, in the county of Delaware and State of Iowa, have invented certain new and useful Improvements in Fence-Post Molds; and I do declare the following to be a full, clear, and exact description of the invention, such as will enable others skilled in the art to which it applies to make and use the same.

This invention relates to improvements in fence-post molds.

The object of the invention is to provide a mold in which fence-posts may be cast or formed from any suitable plastic material, means being provided whereby said material may be firmly tamped into the mold and means whereby the completed post may be quickly and easily removed from the mold.

With the above and other objects in view the invention consists of certain novel features of construction, combination, and arrangement of parts, as will be hereinafter more fully described, and particularly pointed out in the appended claims.

In the accompanying drawings, Figure 1 is a side elevation of the mold, showing the plunger in elevated position. Fig. 2 is a vertical longitudinal sectional view showing the plunger in lowered position and a post formed in the mold. Fig. 3 is a side view showing the parts in a position for removing a completed post. Fig. 4 is a transverse vertical sectional view on a line 4-4 of Fig. 1. Fig. 5 is a similar view on a line 5-5 of Fig. 3; and Fig. 6 is an end elevation of the machine, showing in full lines the parts in position for forming a post and in dotted lines the position of the parts for the removal of a post.

Referring more particularly to the drawings, 1 denotes uprights or standards which are connected together near their lower ends by means of a longitudinally-disposed bar 2, upon which is supported, by means of incline pivot-arms 3, a substantially triangularly-shaped trough 4, which forms one section of the mold. The trough 4 consists of a bottom section or strip 5, to one edge of which is rigidly secured an inclined board 6, forming one of the sides of the mold, and on the other end

of said bottom edge is arranged an inclined board 7, which boards are supported in position by means of V-shaped brace-bars 8. To the brace-bars 8 are secured the upper ends of pivoted arms 3.

On the upper ends of the standards 1 is arranged a plunger-carrying frame 9, said frame being hingedly connected to said standards by means of plates or bars 10, fixed on the ends of the frame and pivotally connected at 60 their lower ends to the standards 1, so that when said frame is in an upright position the same will rest upon the upper ends of the standards 1 and when swung laterally thereon will be supported by said straps or bars 65 10. The lateral movement of said bars 10 and frame 9 is limited by means of a stop-pin 12. The frame 9 is here shown as formed of vertically-disposed upright bars 13, which are connected near their upper ends by a cross-bar 14. On the inner sides of the upright bars 13 are slidably mounted plunger-carrying blocks 15, which are connected by a plunger-bar 16. On one edge of each block 15 is arranged a vertically-disposed rack-bar 17, 70 with which are adapted to mesh spur gear-pinnions 18. The pinions 18 are fixed upon a longitudinally-disposed shaft 19, which is journaled in suitable bearings 20, secured to the adjacent edges of the upright bars 13. 80 On one end of the shaft 19 is arranged a crank-handle 21, whereby said shaft may be revolved to cause said pinions to engage the teeth of said rack-bars, thus raising and lowering the plunger-blocks 15 and plunger 16. 85 On the inner face of the standards 1 and upright bars 13 are arranged guide-rods 22 and 23, whereby said plunger-blocks are guided and held in position. On the upper side of the plunger-bar 16 is arranged a longitudinally-disposed weight, which extends from one end of said bar to the other, whereby an equal pressure will be exerted by the plunger when the same is engaged with the post. On the under side of the plunger is arranged a rib 95 24 and a longitudinally-disposed series of downwardly-projecting pins 25. When said plunger is brought into engagement with the post in the mold said pins are forced through the same and through guide-openings 26, 100

formed in the bottom strip 5 of the mold-trough. The openings thus formed in the post by the pins 25 serve to permit the line-wires of the fence to be passed through the post.

5 In forming a post the parts are brought to the position shown in Fig. 1 of the drawings, wherein the plunger has been raised to its highest position, after which the mold-trough is filled with cement or other plastic material.

10 After that the plunger is allowed to descend upon the plastic mass within said trough, thereby pressing the same into a firm compact form, said plunger being successively raised and dropped upon said mass, thus tamping and packing the same evenly throughout the entire length of the trough. After the post thus formed has begun to set the plunger is raised by means of the crank-shaft, as hereinbefore described, until the same has reached the limit 15 of its upward movement, after which the frame 9 is swung laterally upon the standards 1 to the position shown in Figs. 3 and 5 of the drawings, in which position the same will be entirely clear of the mold-trough, thereby permitting 20 the same to be swung to one side upon the pivotal connections of the arms 3 and into engagement with the supporting cross-bars 27. The bars 27 are arranged upon the connecting-bar 2 of the standards 1, by which said trough 25 will be supported while the post is being removed from the trough, which is readily accomplished by lifting the side board 7, which now forms the bottom supporting-board of the post. Said board is readily removed from 30 the supporting brace-bars 8, and on said board the post is allowed to remain until firmly hardened and set, another board being arranged upon the brace-boards 8 in place of the one removed, after which the trough is swung 35 back to its operative position. The trough 4 is held in an operative position by means of a hook 28, which is pivotally mounted upon the upper end of a bar 29 and is adapted to be hooked into engagement with a pin 30 arranged on the upper edge of the side board 6 of the trough, said side board being adapted to engage the bar 29, which forms a support for this side of the trough. To the side board 40 6 of the trough may be also secured hand-bars 31, whereby the trough may be more readily upset to permit the movement of a finished post therefrom.

As hereinbefore stated, the parts of the mold are preferably so arranged and constructed to 45 form a substantially triangular-shaped post, said parts being also shaped to form a tapering post, whereby the base of the same will be considerably larger than the upper end. It will be obvious that by forming the parts 50 of the mold in a different shape and arranging the same in other positions various-shaped posts may be formed by the machine.

From the foregoing description, taken in 55 connection with the accompanying drawings, the construction and operation of the inven-

tion will be readily understood without requiring a more extended explanation.

Various changes in the form, proportion, and the minor details of construction may be resorted to without departing from the principle or sacrificing any of the advantages of 70 this invention.

Having thus described my invention, what I claim as new, and desire to secure by Letters Patent, is—

1. In a mold of the character described, the combination with a supporting-frame, of a mold-trough hingedly connected thereto, one side of said trough being adapted to be removed, a tamping-plunger arranged above 80 said trough, guide-rods on said plunger, means whereby said plunger is raised and lowered, and means whereby the same may be swung laterally to clear said trough, substantially as described.

2. In a mold of the character described, the combination with a supporting-frame, of a mold-trough arranged thereon, means whereby said trough may be swung to a horizontal position on said frame, means whereby one 90 of the side boards of the trough is detachably supported to permit the same to be lifted from the trough thus facilitating the removal of a finished post, a plunger-supporting frame arranged above and hingedly connected to said standards, a tamping-plunger slidably mounted in said frame, and means whereby said plunger is raised and lowered, substantially as described.

3. In a mold of the character described, the 100 combination with a supporting-frame, of a mold-trough arranged therein, supporting-arms connected at their upper ends to said trough and hingedly connected at their lower ends to said frame, V-shaped brace-bars connected to one of the side boards of said trough and adapted to removably support the other side board, a plunger-frame arranged above and hingedly connected to said standards, a tamping-plunger slidably mounted in said 105 frame, guide-rods arranged on said frames to guide said plunger in its movement, and means whereby said plunger is raised and lowered, substantially as described.

4. In a mold of the character described, the 110 combination with a supporting-frame, of a mold-trough arranged therein, supporting-arms connected at their upper ends to said trough and hingedly connected at their lower ends to said frame, whereby said mold may be tilted to a horizontal position, means whereby the same is supported in said horizontal position, V-shaped brace-bars connected to one of the side boards of the mold and adapted to removably support the other side board, a weighted plunger-frame hingedly mounted on the upper ends of said standards, a plunger 115 slidably mounted in said frame, pins arranged on the under side of said plunger to engage holes formed in the bottom of said 120

trough, guide-rods arranged on said frames, to guide said plunger in its movements, and means whereby said plunger is raised and lowered, substantially as described.

5 5. In a mold of the character described, the combination with a supporting-frame, of a mold-trough arranged therein, supporting-arms connected at their upper ends, to said trough and hingedly connected at their lower ends to said frame, V-shaped brace-bars connected to one of the side boards of said trough and adapted to removably support the other side board, a plunger-frame arranged above and hingedly connected to said standards, a

15 tamping-plunger slidably mounted in said

frame, guide-rods arranged on said frames, to guide said plunger in its movement, rack-bars arranged on said plunger, an operating-shaft journaled on said plunger-frame, pinions fixed on said shaft to engage said rack-bars 20 whereby when said shaft is turned in one direction or the other said plunger will be raised or lowered, and means whereby said shaft is turned, substantially as described.

In testimony whereof I have hereunto set my 25 hand in presence of two subscribing witnesses.
